ALEXANDER GIRTANNER AND ROBERT H. MILLER, OF ST. LOUIS, MISSOURI, ASSIGNEES,
BY MESNE ASSIGNMENTS, TO AMERICAN STEAM CONVEYOR CORPORATION, OF
CHICAGO, ILLINOIS, A CORPORATION OF NEW YORK.

ASH-CONVEYER SYSTEM.

1,273,849.

Specification of Letters Patent. Patented July 30, 1918.

Application filed April 29, 1915. Serial No. 24,628.

To all whom it may concern:

Be it known that we, ALEXANDER GIRTANNER and ROBERT H. MILLER, citizens of the United States of America, residing at the 5 city of St. Louis, State of Missouri, have invented a certain new and useful Ash-Conveyer System, of which the following is such a full, clear, and exact description as will enable any one skilled in the art to which it 10 appertains to make and use the same, reference being had to the accompanying drawings, forming part of this specification.

Our invention relates to an ash conveyer system and has for its principal object the 15 production of a system which may be used to efficiently convey ashes for a considerable distance.

Our invention also consists of certain novel details of construction, all of which 20 will be described in the specification and pointed out in the claims appended hereto.

In the drawings, Figure 1 is a diagrammatic representation of a system made in accordance with our invention; Fig. 2 is an 25 enlarged sectional view showing the booster jet; Fig. 3 is a section taken on the line 3—3 of Fig. 2; Fig. 4 is an enlarged sectional view of the lower elbow; and Fig. 5 is a view partly in elevation and partly in 30 section showing the manner of applying the baffle plates.

Like marks of reference refer to similar parts in the several views of the drawings.

10 represents the vertical portion of the conduit. This vertical portion 10 is secured by any suitable fastening means 11 to the wall 12. An opening 13 is formed in the wall 12 through which passes the upper elbow 14 from which the conveyer leads to 40 any suitable discharge point. This elbow 14 is provided with one of the main injector jets supplied by a steam pipe 15. The construction of the elbow 14 is like that shown in the application of Alexander Girtanner, 45 Serial No. 21,548, filed April 15, 1915, and need not be described in the present application. The lower portion of the vertical part 10 of the conduit is preferably supported by uprights 16 engaging with a collar 17 surrounding the conduit.

The lower end of the portion 10 is connected with the horizontal portion of the conduit by an elbow 18. This elbow 18 is shown in detail in Fig. 4 of the drawings.

It consists of an inner curved portion 19, 55 a back 20 and a bottom 21. The back 20 and bottom 21 are substantially straight and are secured to the portion 19 by means of lugs 22 through which pass bolts 23 (see Fig. 1). The bottom piece 21 has secured 60 in it a removable jet 24 forming one of the main injector jets. This jet 24 is supplied with steam by a pipe 25. The bottom 21 and back 20 have formed in them an opening receiving a wear plate 26. This wear plate 65 26 is held in position by means of a spring bar 27 engaging with lugs 28 on the back and bottom pieces. While the bottom 21 is substantially straight in contour, as hereinbefore stated, it has on its inner surface 70 an inclined guiding face 29 for delivering ashes to the steam jet at an angle. The face of the wear plate 26 is also preferably inclined, as shown in the drawings, to assist in guiding the ashes into the conduit 10. 75

The elbow 18 connects the vertical part 10 of the conduit with the horizontal part which consists of a portion 30, preferably of the same diameter as the part 10, and a portion 31 which is of less diameter than the 80 said part 30. This portion 31 is situated at the opposite end of the conduit from the discharge end. We have found that by using a conduit, the horizontal portion of which is composed of two different diameters, the smaller being farthest from the discharge end, we are enabled to convey the ashes much more economically and also to handle the ashes at the extreme end of the conveyer much more rapidly. The ashes 90 enter the parts 30 and 31 of the conveyer through hoppers 32 from furnaces (not shown). While we are enabled to increase the efficiency of the device by using the two different diameters of conveyer in the horizontal portion, we find that unless some means is provided for keeping the ashes in the large portion agitated, the fine ashes are liable to collect at the bottom and obstruct this portion of the conveyer. In 100 order to accomplish this agitation of the ashes, we form in the large portion 30 of the conveyer a number of openings 33 adapted to receive members 34 forming inclined baffle plates for forcing the air downwardly. 105 These baffle plates 34 are arranged along the upper side of the large portion 30 of the conveyer at approximately regular in-

tervals. These baffle plates 34 being removable, are readily replaced in case they become worn.

In order to assist the main injector jets 5 15 and 24, it is sometimes necessary to provide one or more booster jets in the horizontal portion of the pipe. One such booster jet is shown at 35. This jet is set into a portion of the conveyer 30 so as to be 10 removable and is secured in position by bolts 36. It is supplied with steam by a steam pipe 37. This jet enters the horizontal portion of the conveyer from the lower side so that its action is to tend to lift any ashes 15 which deposit in the bottom of the conveyer and thus assist the baffle plates 34 in preventing this deposit of fine ashes on the bottom of the conveyer.

The operation of our conveyer will be obvious. Steam is admitted through the pipes 20 15, 25 and 37 and the ashes are admitted through the hoppers 32. The elbow 18 can be readily renewed in its back and bottom parts if the same become worn and the wear 25 plate 26 which receives the greatest amount of wear from the ashes is also readily renewable. The baffle plates 34, while they reduce the area of the pipe at certain points, do not add materially to the friction 30 between the steam and ashes and the pipe so that the friction in the large pipe 30 is substantially the same as though the baffle plates were not present and, at the same time, the baffle plates keep the fine ashes in 35 suspension in this portion of the pipe.

Having fully described our invention, what we claim as new and desire to secure by Letters-Patent of the United States is:

1. In an ash conveyer system the combination with a horizontally arranged conduit provided with spaced inlet openings, of means for creating a flow of fluid therethrough, and means arranged at intervals in said conduit between said inlet openings and 40 45 at positions where the flow of fluid through said conduit would otherwise be substantially uniform for successively deflecting the fluid toward the bottom of said conduit comprising a plurality of spaced baffles projecting downwardly into said conduit and inclined in the direction of flow of said fluid.

2. In an ash conveyer system the combination with a horizontally arranged conduit

provided with spaced inlet openings, of means for creating a flow of fluid therethrough, and means arranged at intervals in said conduit between said inlet openings and at positions where the flow of fluid through said conduit would otherwise be substantially uniform for successively deflecting the fluid toward the bottom of said conduit comprising a plurality of spaced baffles projecting downwardly into said conduit.

3. In an ash conveyer system the combination with a horizontally arranged conduit provided with spaced inlet openings, of means for creating a flow of fluid therethrough, and means arranged at intervals in said conduit between said inlet openings and 60 70 at positions where the flow of fluid through said conduit would otherwise be substantially uniform for successively deflecting the fluid toward the bottom of said conduit.

4. In an ash conveyer system the combination with a horizontally arranged conduit provided with spaced inlet openings, of means for creating a flow of fluid therethrough, and means arranged in said conduit at a position between said inlet openings where the flow of fluid through said conduit would otherwise be substantially uniform for deflecting the fluid toward the bottom of said conduit.

5. In an ash conveyer system the combination with a horizontally arranged conduit, of means for creating a flow of fluid therethrough, means arranged in said conduit at a position where the flow of fluid through said conduit would otherwise be substantially uniform for deflecting the fluid toward the bottom of said conduit comprising a baffle plate, and means co-acting with said baffle plate comprising an injector nozzle 90 95 extending through the bottom of said conduit and discharging against the inclined face of said baffle.

In testimony whereof, we have hereunto set our hands and affixed our seals in the presence of the two subscribing witnesses.

ALEXANDER GIRTANNER. [L. S.]

ROBERT H. MILLER. [L. S.]
